Primary Examiner — Austin Murphy(57) **CLAIM**

The ornamental design for a dish drying rack, as shown and described.

DESCRIPTION

FIG. 1 is a perspective view of a dish drying rack showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the dish drying rack where the dish drying rack is in a rolled-up state; and,

FIG. 10 is a left side elevational view of the dish drying rack where the dish drying rack is in the rolled-up state.

The dish drying rack is shown with a symbolic break in its length and the appearance of any portion of the dish drying rack between the break lines form no part of the claimed design.
